EDGAR M. GRUEN, OF NEW YORK, N. Y.

CLASP FOR SANITARY BELTS.

Application filed December 4, 1923. Serial No. 678,478.

To all whom it may concern:

Be it known that I, EDGAR M. GRUEN, a citizen of the United States, and resident of the borough of the Bronx, in the county of the Bronx, city and State of New York, have invented certain new and useful Improvements in Clasps for Sanitary Belts, of which the following is a specification.

The main object of this invention is to provide an effective clasp of simple construction readily operable to clasp the reduced end of a sanitary pad or napkin.

A further object of the invention is to provide a clasp that may be quickly operated to release the pad by an outward and upward pull on the end of the pad.

A clasp constructed in accordance with this invention while especially adapted for the use herein indicated, may be used for many purposes, for instance, as a garment supporter and for other like uses.

The invention is designed particularly for use with the well known Kotex pads, but of course, it is capable of use with any form of pad or napkin having soft or reduced ends adapted to be grasped firmly between the clasp members.

In the drawing:

Fig. 1 is a front view of the device showing one end of a pad secured thereto;

Fig. 2 is a perspective view of the clasp open and detached from the holding belt;

Fig. 3 is a view similar to Fig. 2 showing clasp in closed or gripping position;

Fig. 4 is a view similar to Fig. 3 showing the reverse side of the clasp;

Fig. 5 is a vertical longitudinal sectional view of the clasp in open or released position, and taken approximately on the line 5—5 of Fig. 2;

Fig. 6 is a vertical sectional view similar to Fig. 5, showing the clasp in a partly closed position;

Fig. 7 is a front view showing the clasp in a position corresponding to Fig. 6;

Fig. 8 is a vertical longitudinal sectional view taken on the line 8—8 of Fig. 1;

Fig. 9 is a transverse sectional view taken on the line 9—9 of Fig. 8;

Fig. 10 is a vertical sectional view similar to Fig. 8 showing the manner of releasing

the clasp by an outward and upward pull on the end of the clasped fabric element; and

Fig. 11 is a view similar to Fig. 10 showing the position of the parts in a more advanced stage of the releasing operation.

Referring to the various parts by numerals, 1 designates the lower portion of a belt of any desired form. To this belt is secured a depending fabric tape 2 to the lower end of which the clasp is connected. The clasp consists of a body part 3 and a tubular clamping slide 4 mounted on the body part and arranged to move longitudinally up and down thereon.

The body part of the clasp is formed of a comparatively narrow plate of sheet metal having a slot 5 near its upper end to receive the tape 2. A suitable distance from its lower or free end the plate 3 is formed with a mouth 7 which is in the form of a transverse slot extending inwardly and transversely of the plate 3 from the left hand edge, as shown clearly in Fig. 3. This slot separates the clasp head 8 from the body of the plate, said head being connected to the plate 3 by a neck 9 at the right hand edge of the plate, the inner edge of said neck forming the inner wall of the mouth 7. A portion of the plate 3, along the upper margin of the mouth 7 is bent forwardly to form a stop 10, said stop extending transversely of the plate 3. This stop is cut away and rounded at its outer or left hand corner 11 to provide clearance for the insertion of the fabric into the mouth 7. The side edges of the head are formed with forwardly extending longitudinal flanges 12 and 13. The flange 13 extends along the outer or right hand edge of the neck 9 and above said neck to strengthen it. These flanges form a channel in which the material to be clamped may be conveniently arranged and also serve as guides for the clamping slide. The upper edge of the head 8, which forms the lower margin of the mouth 7, is serrated or toothed, as shown, to securely hold the fabric clamped over the head and the flange 12 is extended above the level of said teeth to prevent accidental sidewise removal of the fabric from the teeth. The head 8 is dished

or bulged forwardly between the flanges 12 and 13 to form the hollow or concave back 14 and the convex forward side 15, said parts being curved both longitudinally as well as transversely of the head. The convex forward side of the head is formed with transversely extending serrations in the form of sharp teeth 16 into which the fabric is forced by the clamping slide. It will be noted that the teeth 16 do not project beyond the outer longitudinal edges of the flanges 12 and 13. The body portion 3 of the clasp is formed with a yieldable portion 17 which extends centrally and longitudinally from a point adjacent the stop flange 10 to a point adjacent the slot 5. This yieldable portion is in effect a leaf spring and is formed by spaced vertically extending slits in the plate 3 connected at their upper ends by a horizontal slit. Formed upon the spring 17 a suitable distance above its lower end is a forwardly projecting transverse locking ridge or hump 18. This ridge is formed by pressing the metal of the plate 3 forwardly. A transverse ridge or hump 19 is formed in the plate 3 at one side of the spring 17 and a slight distance above the ridge 18. The ridge 19 projects rearwardly from the reverse face of the plate 3 and is formed by pressing the metal of the plate rearwardly. The upper end of the spring 17 is free and is bowed forwardly to form a hump 20.

The clamping slide 4 is open ended and tubular and slides readily longitudinally of the plate 3 and over the flanges 12 and 13. It is of sufficient length to substantially enclose the head 8 and the mouth 7. The upper edge of the forward wall of the slide is provided with an upwardly extending locking tongue 21 whose free end is bent inwardly to engage and ride on the forward face of the plate 3 above the mouth 7. The clamping slide is also formed upon its reverse side with a pair of upwardly extending guide fingers 22. These fingers are spaced apart to provide clearance for the spring 17 and their upper ends extend above the level of the inturned locking tongue 21 and are turned in slightly to engage and ride on the rear face of the plate 3 at opposite sides of the spring 17.

The operation of the device is as follows:

The clamping slide is first moved up to the position shown in Figs. 2 and 5. In moving the slide to this position the spring 17 is pressed rearwardly by reason of the engagement of the fingers 22 and tongue 21 with the opposite faces of the plate 3. The tongue 21 then rides over the hump 20 of the spring after which the hump springs forwardly beneath the tongue and the clasp is held thereby in its upper position. The soft reduced end of the pad or napkin is passed into the mouth 7 inwardly of the up-

per end of the flange 12 and then folded forwardly down over the convex side of the head 8 between the flanges 12 and 13. The slide is then forced down, the tongue 21 forcing back the hump 20 and the tubular portion of the slide forced down over the folded fabric and over the flanges 12 and 13, thereby forcing the fabric into close contact with the teeth 16 and into the hollow part 14. As the clasp is moved down the finger 22 rides over the ridge 19 upon the rear of the plate and falls into place below said ridge.

The Kotex pad or other fabric is released from the clasp by moving the clamping slide up on the plate 3. This may be done readily by pulling outwardly and upwardly on the ends of the fabric as illustrated in Fig. 6. The pull of the fabric results in an upward thrust on the slide 4. The upward movement of the slide causes the finger 22 to first engage and ride over the rear ridge 19, and the finger 22, tongue 21 and the humps 18 and 19 are so spaced that when the finger 22 is upon the high point of the ridge 19 the tongue 21 will be pulled thereby into contact with the base of the ridge 18. Upon further upward movement of the slide the tongue rides over the ridge 18 and the hump 20 against the resistance of the spring. The mouth 7 is then uncovered and the fabric may be removed from the clasp.

In case the user should fail to push the slide 4 down to the lower limit of its movement but merely pushes it down until the tongue 21 passes over the hump 20, the fabric will in ordinary service still be held securely. The parts of the clasp are so proportioned that when the tongue 21 is below the hump 20 the tubular part of the slide extends below and encloses the mouth 7 as shown in Figs. 6 and 7. A tension upon the main or inner strand of the fabric will then cause the fabric to bind upon the teeth of the mouth 7 and upon the lower edges of the slide 4 and be held thereby.

What I claim is:

1. A clasp comprising a body part formed with a head at its lower end, a laterally extending open mouth being formed between the head and the main body of the clasp, a transverse stop flange formed on the body part along the upper transverse margin of the said mouth, a leaf spring carried by the said body part, a locking hump carried by the spring and spaced above the said stop flange, and a clamping slide mounted to move longitudinally on the body part and formed with a locking tongue adapted to ride over the locking hump and to rest in the space between the locking hump and the stop flange when the slide is in its clamping position.

2. A clasp comprising a body part formed with a head at its lower end, a laterally ex-

tending open mouth being formed between the head and the main body of the clasp, a stop formed on the body part above the said mouth, the said main body being formed 5 with a yieldable resilient portion, a locking hump carried by said yieldable portion and spaced above the said stop, a rigid hump formed upon the opposite side of the main body from the yieldable hump, and a clamping 10 slide mounted to move longitudinally on the body part and formed with a locking tongue adapted to ride over the yieldable hump and to rest in the space between said hump and the stop when the slide is in its 15 clamping position, the said slide being designed in its initial opening movement to engage the said rigid hump in advance of the engagement of the locking tongue with the yieldable locking hump whereby the 20 said tongue is moved inwardly and caused to engage the base of said locking hump.

3. A clasp comprising a body part formed with a head at its lower end, a laterally extending open mouth being formed between the head and the main body of the clasp, a transverse stop flange formed on the body part along the upper transverse margin of the said mouth, a clamping slide mounted to move longitudinally on the body 25 part, a locking tongue on the slide adapted to engage the stop flange, and means for yieldably holding the clamping slide in a full clamping position and in an intermediate clamping position the said slide being 30 designed to enclose the said mouth of the clasp in either of the said clamping positions.

4. A clasp comprising a body part formed with a head at its lower end, a laterally extending open mouth being formed between the head and the main body of the clasp, a transverse stop flange formed on the body part along the upper transverse margin of the said mouth, the said main body part being formed with a pair of spaced longitudinally extending slits and the portion between said slits being yieldable and resilient, a lower locking hump formed on the said yieldable portion and spaced from the 40 transverse stop flange, an upper locking hump formed on the yieldable portion and spaced above the lower hump and a clamping slide mounted to move longitudinally on the body part and formed with a locking 45 tongue adapted to ride over the said yieldable locking humps and adapted when the slide is in clamping position to rest between the lower hump and the transverse stop flange and when the slide is in unclamping position to rest upon the upper side of the upper hump and be held thereby.

5. A clasp comprising a body part formed with a head at its lower end, said head being bulged forward to form a convex gripping 50 surface, a laterally extending open mouth

with teeth at its lower margin being formed between the head and the main body of the clasp, a transverse stop flange formed on the body part along the upper transverse margin of the said mouth, flanges extending 70 along the longitudinal edges of the head, a clamping slide mounted to move longitudinally on the body part and adapted to slide to clamping position over the head and the flanges thereon, and means for yieldably 75 holding the slide in a lower full clamping position and in an intermediate clamping position, the said slide being adapted to enclose the head and the mouth of the clamp in full clamping position and enclose the 80 mouth in said intermediate position.

6. A clasp comprising a body part formed with a head at its lower end, a laterally extending open mouth being formed between the head and the main body of the clasp, a transverse stop flange formed on the body part along the upper transverse margin of the said mouth, the said main body part being formed with a pair of spaced longitudinally extending slits and the portion between said slits being yieldable and resilient, a lower locking-hump formed on said yieldable portion and spaced from the transverse stop flange, an upper locking hump 90 formed on the yieldable portion and spaced above the lower hump, a rigid hump formed upon the opposite side of the main body from the said yieldable humps, and a tubular clamping slide mounted to move longitudinally on the body part and formed with 95 a locking tongue adapted to ride over the said yieldable humps and adapted in the lower clamping position of the slide to rest between the lower hump and the transverse stop flange, and adapted to rest and be held supported upon the upper side of the upper locking hump in the upper unclamping position of the slide, the said slide being designed in its initial unclamping movement 100 to engage the said rigid hump in advance of the engagement of the locking tongue with the lower yieldable hump whereby the tongue is moved inwardly to engage the base of said yieldable hump.

7. A clasp comprising a body part formed with a head at its lower end, a laterally extending open mouth being formed between the head and the main body of the clasp, a clamping slide movable longitudinally upon the main body and adapted to enclose the 110 head and mouth in its lower clamping position, and a flat locking spring integral with the main body extending longitudinally thereof and formed to engage the slide and yieldably hold it in its clamping and unclamping positions.

8. A clasp comprising a body part formed with a head at its lower end, a laterally extending open mouth being formed between the head and the main body of the clasp, a 130

4
transverse stop flange formed on the body part along the upper transverse margin of the said mouth, a clamping slide mounted to move longitudinally on the body part and formed with a locking tongue and a pair of yieldable locking devices carried by the body part and over which the said locking tongue is adapted to ride, one of said devices being

adapted to yieldably hold the tongue in the closed position of the clamping slide and the other device to yieldably hold the tongue in the open position of the slide. 10

In testimony whereof I hereunto affix my signature.

EDGAR M. GRUEN.
